UNITED STATES PATENT OFFICE.

CHRISTY J. BAUMANN, OF PITTSBURGH, PENNSYLVANIA, ASSIGNOR TO MACBETH-EVANS GLASS COMPANY, OF PITTSBURGH, PENNSYLVANIA, A CORPORATION OF PENNSYLVANIA.

DESIGN FOR A BOTTLE.

Application filed November 10, 1926. Serial No. 19,666. Term of patent 7 years.

To all whom it may concern:

Be it known that I, CHRISTY J. BAUMANN, a citizen of the United States, residing at Pittsburgh, in the county of Allegheny and State of Pennsylvania, have invented a new, original, and ornamental Design for Bottles, of which the following is a specification, reference being had to the accompanying drawing, forming a part thereof.

The figure is an elevation of a bottle showing my new design.

I claim:

The ornamental design for a bottle as shown.

CHRISTY J. BAUMANN.
